Benjamin E. Lawrence, Chicago, Ill.

Application August 28, 1943, Serial No. 111,008

Term of patent 7 years

(Cl. D52—7)

To all whom it may concern:

Be it known that I, Benjamin E. Lawrence, a citizen of the United States, residing at Chicago, in the county of Cook and State of Illinois, have invented a new, original, and ornamental Design for a Combined Thermometer and Barometer or the like, of which the following is a specification, reference being had to the accompanying drawing, forming a part thereof.

In the drawing—

Fig. 1 is a front elevational view of a combined thermometer and barometer, showing my new design.

Fig. 2 is a side elevational view, and

Fig. 3 is a plan view.

I claim:

The ornamental design for a combined thermometer and barometer or the like, as shown.

BENJAMIN E. LAWRENCE.
